UNITED STATES PATENT OFFICE.

JAMES F. McELROY, OF ALBANY, NEW YORK, ASSIGNOR TO THE CONSOLIDATED CAR-HEATING COMPANY, OF SAME PLACE.

ELECTRIC HEATER.

SPECIFICATION forming part of Letters Patent No. 598,638, dated February 8, 1898.

Application filed March 24, 1894. Serial No. 504,944. (No model.)

To all whom it may concern:

Be it known that I, JAMES F. McELROY, a citizen of the United States, residing in the city and county of Albany, State of New York, 5 have invented a new and useful Improvement in Electric Heaters, of which the following is a specification.

My invention relates to improvements in mechanism for heating by electricity; and the 10 object of my invention is to provide a heater particularly adapted for use in drying barrels, casks, &c. I accomplish this object by means of the mechanism illustrated in the accompanying drawings, in which—

15 Figure 1 is a side elevation. Fig. 2 is an inverted plan. Fig. 3 is an end elevation. Fig. 4 is a detail view of the end of the frame; and Fig. 5 is a section of a cask, showing the heater placed therein.

20 Similar letters refer to similar parts throughout the several views.

In coopers' establishments it is considered extremely dangerous to have a burning fire, because of the shavings and dried lumber which usually abound therein. The ordinary way of drying a barrel or a cask is to place a pan or a pail containing hot coals or fire within the same, and it is to avoid the danger of igniting the combustible material 25 in the shop and to provide a more efficient source of heat that the invention herein described was made. As I propose to use electricity as the heating agent and as the persons who are to use the heater will be men 30 unskilled in the use of electrical apparatus, I have provided a heater which may be safely handled, preventing danger from being burned by a careful arrangement of the wires carrying the current, and which will perform 35 the results required of it regardless of the position in which it lies, whether on one side or the other or on either end.

Referring to the drawings, I arrange one or more spindles A A' A², (three being shown,) 45 constructed of non-conducting material, preferably porcelain, each provided with a groove a, extending spirally from one end to the other thereof, within which groove I place a resistance B, preferably in the form of a helix, and 50 mount the spindle or spindles within the frames C C. In the frame C, I preferably arrange a collar c, in which I fit tubes or pipes

D D', thus providing two pipes D D', extending from one end of the heater to the other in the lower portion of each side thereof. I 55 usually employ three spindles and mount them in the frame at each end thereof by means of a bolt E, suitably insulated, extending, preferably, through the spindle, and where two spindles adjoin each other at the 60 end, as shown in Figs. 1 and 2, the bolt passes through them both. The bolt E is secured at each end in plates E' E', said plates resting upon the chairs E², (see Fig. 4,) thus arranged so that by the removal of the plates 65 E' the spindles may be taken out of the heater. Between the ends of the spindles I arrange a suitable non-conducting plate F, preferably porcelain, which carries binding-posts k' k' and is perforated to admit of the passage of 70 the bolts E and placed at the junction of adjacent spindles on the bolts E. A series of rods R extend from one end piece to the other, provided with nuts or other adjusting devices on the ends for the purpose of holding the parts of the heater securely together. The tubes or pipes D D are threaded at one 75 end only, the end which is unthreaded fitting into the collar c, they being so arranged for the purpose of providing for a rapid and simple method of setting up and taking apart 80 the heater. Thus when the nuts are removed from the rods R the tubes or pipes may be withdrawn by pulling them out of the collar, the bolts E', carrying the spindles, removed, 85 and the heater is dismembered. For the purpose of transporting the heater conveniently I arrange at each end a handle or bail G.

I connect up the heater in the following manner: H represents the live wire, and h h' 90 cut-outs. When the current is cut out at h, the cut-out h' being closed, the current passes into the wire J, which wire passes into and through the pipe D' and connects with the binding-post j at the opposite end of the heater. The 95 binding-post j is connected to the coils on two of the spindles A' and A², and those coils are placed in circuit. The return-wire K enters the pipe D and is connected by the wire k to the binding-posts k' k', connected 100 with each of the spindles. The binding-post j' is also connected with the coil on each of the spindles A' A² and to the wire J, and electricity therefore enters from both ends of

the spindles. When the wire J is cut out at h', the cut-out h being closed, the wire L carries the electricity through the pipe D' and is connected to the binding-post l, which is 5 connected to the coil on the spindle A. The end of the coil on the spindle A opposite the contact-post l is in contact with the contact-post l', which is connected with the wire L, and the coil is connected to the return-wire, 10 K by the wire k. In this state of the cut-outs the coil on the spindle A alone is in circuit. Thus I am enabled to shunt out one or two of the coils or use them all together, as desired. 15 The object in carrying the wires through the tubes or pipes D D' is to prevent short-circuiting the coils. If they were left exposed, there would be danger of the wire coming in contact with the resistance on the 20 spindles, and there is also the additional reason that if they were left uncovered they would be liable to burn the operator in handling the heater. Furthermore, if they were not protected they might come in contact with 25 the sides of the cask or barrel when in use or with foreign substances when not in use, which would be liable to break the wires. Thus by placing them within the pipe they are protected from injury to the wire from 30 short-circuiting, which would injure the apparatus, and from doing damage to the person using the heater.

By arranging the spindles in short sections and connecting them up as indicated I can 35 make my heater more economically, because of the short porcelains being less expensive, and by thus uniting two or more spindles on

one bolt I provide for placing the binding-posts between the ends of the heater. By this arrangement I provide for charging the heaters from the ends and having the terminals between the ends of the heater, thus making a wide separation of the positive and negative wires, the object being to make this heater as simple as possible for the use of 40 men unaccustomed to electrical devices. As thus arranged my heater is open on all sides and the ends, providing for the circulation of air around the heating-coils, regardless of the position in which the heater may be placed, 45 the wiring and connecting up of the several coils of the heater is within the pipes, and the whole is so connected together that in case of accident or injury accruing to any of its parts it may be quickly taken apart and 50 repairs made with little inconvenience or loss of time or expense in operation.

What I claim as my invention, and desire to secure by Letters Patent, is—

An electric heater, consisting of end pieces, 60 each provided with a chair, a series of tubes secured in said end pieces, supply and return conductors arranged within said tubes plates adapted to rest in said chairs, a spindle connected with said plates, a coiled resistance 65 on said spindle, said resistance-carrying spindle placed intermediate of said tubes, and a series of rods passing from one end piece to the other, substantially as described.

JAMES F. McELROY.
